[57] CLAIM

The ornamental design for a simulative clock, as shown
and described.

DESCRIPTION

FIG. 1 is a front elevational view of a simulative clock
showing my new design;
FIG. 2 is a right side elevational view thereof;
FIG. 3 is a top plan view thereof;
FIG. 4 is a bottom plan view thereof;
FIG. 5 is a left side elevational view thereof;
FIG. 6 is a rear elevational view thereof;
FIG. 7 is a front elevational view of another embodiment
of my new design of FIGS. 1-6, all other views
being substantially similar thereto.
